BATHTUB

Forrest Additon, Flowery Branch, Ga.

Application March 16, 1936, Serial No. 69,175

7 Claims. (Cl. 4—173)

This invention relates to a bathtub and has for its object to provide, in a manner as hereinafter set forth, a tub of the class referred to so constructed and of such internal dimensions as to 5 reduce liability of accidents to a minimum in case the user slips therein.

A further object of the invention is to provide, in a manner as hereinafter set forth, a bathtub free of pipes and faucets internally thereof and 10 of a size to prevent a long slip therein of the user whereby liability of injury is materially reduced.

A further object of the invention is to provide, in a manner as hereinafter set forth, a bathtub having the upper portion of its body formed with 15 means for spraying the back, sides and front of body of user to constitute a water shower thereby eliminating, for such purpose the generally employed overhead water showering appliances.

A further object of the invention is to provide, in a manner as hereinafter set forth, a bathtub of internal dimensions to prevent a long slip therein by the user whereby liability of accidents is reduced to a minimum; having one of its walls so formed to constitute an internal seat for the 25 user; and with the upper portion of the body of the tub having means to provide for water showering the back, sides and front of the body of the user.

A further object of the invention is to provide, in a manner as hereinafter set forth, a bathtub of dimensions which would greatly reduce the 30 space required for bathrooms, as well as eliminating the messy overhead shower appliances, but at the same time possessing water spraying or showering advantages.

A further object of the invention is to provide, in a manner as hereinafter set forth, a bathtub of dimensions which would greatly reduce the space required for bathrooms; having one of its 35 walls formed in a manner to provide an internal seat for the user; having its upper end formed in a manner to provide an endless water conducting passage for communication with a water supply; and having its body formed with inwardly extending inclined ports opening into said passage for spraying the back, sides and front of the body of a person seated within the tub.

Further objects of the invention are to provide, in a manner as hereinafter set forth, a bathtub of materially reduced dimensions than that of the tubs now generally used, which is strong, durable, compact, thoroughly efficient for the purpose intended thereby, and comparatively inexpensive to manufacture.

With the foregoing and other objects which

may hereinafter appear, the invention consists of the novel construction, combination and arrangement of parts as will be more specifically described and are as illustrated in the accompanying drawing wherein is shown an embodiment of the invention, but it is to be understood that changes, variations and modifications may be resorted to which fall within the scope of the invention as claimed.

In the drawing:

Figure 1 is a top plan of the bathtub, Figure 2 is a section on line 2—2 Figure 1, and Figure 3 is a section on line 3—3 Figure 1.

The tub 4 may be of any suitable height and of any suitable contour in plan. Preferably, the 15 contour of tub 4 will be square and it is so shown. The tub 4 includes a front wall 5, a rear wall 6, a pair of side walls 7, 8, and a bottom 9. The wall 5 is of angle-shape in vertical section and formed of a vertical upper portion 10, a horizontally disposed intermediate portion 11, and a vertical lower portion 12. The portion 11 extends inwardly from the lower end of portion 10 and merges into the upper end of portion 12. The portion 11 constitutes a seat 13 for the user. The points of 20 emergence of the portion 11 with the portions 10, 12 are rounded. The wall 6 is straight and of square contour, of substantially inverted L-shape contour. The walls 7, 8 are straight and each consists of an upper portion 14 and a lower portion 15. The latter is of less width and height than the portion 14. The portions 14 merge into the portions 10 and 11 of the wall 5 and into the upper portion of wall 6. The portion 15 merges into the portion 12 of wall 5 and into the lower portion of 25 wall 6. The height of the walls 5, 6, 7 and 8 will be the same.

The bottom 9 in plan corresponds in contour to that of the top of tub 4 and is shown as square. The bottom 9 is flat and formed integral with the 30 lower end of portion 12 of wall 5 and the lower ends of the walls 6, 7 and 8. The manner of setting up the bottom 9 relative to the walls 5, 6, 7, 8, forms it with an extension 16 free of said walls and opposing in spaced relation the portion 11 of wall 5. The extension 16 acts as a means 35 to prevent the tilting of the tub when the bottom is positioned flat upon the floor.

The shape of the walls 5, 7, 8, in connection with the square rear wall 6 provides the tub with 40 a chamber 17 having its upper portion of greater dimensions than its lower portion.

Preferably the portion 10 of wall 5 will be of 45 slightly greater height than portion 12 and it is so shown. Preferably the height of portion 12 50

10

20

25

30

35

40

45

50

55

will be about a foot whereby the seat formed by portion 11 of wall 5 will be elevated about a foot. The walls of the tub will be practically no higher than the height of the ordinary bathtub with feet.

5 The cross sectional length of the seat 13 will correspond substantially to the height of the portion 12 of wall 5.

The upper end of the wall 5 is formed with an outwardly directed hollow bead 18 providing a channel 19. The upper ends of the walls 6, 7 and 8 are formed with inwardly directed beads 20, 21 and 22 respectively providing channels 23, 24 and 25 respectively. The channels open into each other and form an endless water conducting passage 26. The walls 5, 6, 7 and 8 adjacent their upper ends are provided with spaced spray ports 27, 28, 29 and 30 respectively disposed at a downwardly inclination, preferably at an angle of 45° and which open at their lower ends at the inner faces of the said walls. The upper ends of the ports 27, 28, 29 and 30 open into the channels 19, 23, 24 and 25 respectively. The ports provide for directing water in a shower-like form against the back, sides and front of the occupant of the tub.

25 A water supply connection is indicated at 31 and which is shown by way of example as opening into channel 23. An outlet for chamber 17 is shown at 32. The outer side faces of the walls 6, 7 and 8 are squared.

30 The preferred installation of the tub would be to have it built in with bottom 9 sunk about a foot below floor level.

The dimension of the tub will be such as to prevent a long slip therein by the occupant thereof, whereby liability of accidents would be reduced to a minimum, then further as the interior of the tub is free of faucets or pipe nozzle, a further provision is had to prevent injury to the user.

What I claim is:

40 1. A bathtub including an open top integral body formed of a bottom and front, rear and side walls, said front wall being of angle-shape contour and having an intermediate part thereof directed inwardly to provide a seat within said body extending from one side wall to the other, elevated above said bottom and spaced from said rear walls, and said walls provided with means disposed throughout their upper terminal portions for directing a multiplicity of jets of water 50 to impact the back, sides and front of occupant of the tub.

2. A bathtub including an open top integral body formed of a bottom and front, rear and side walls, said front wall being of angle-shape contour and having an intermediate part thereof directed inwardly to provide a seat within said body extending from one side wall to the other, elevated above and opposing a portion of said bottom and spaced from said rear wall, said side walls being substantially of inverted L-shape and having their front edges flush with the outer face of said front wall, the lower ends of said side and front walls merging into said bottom rearwardly of said seat, said walls provided with means at their upper ends for directing a water shower to impact the back, sides and front of occupant of the tub, and said means consisting of an endless water passage completely around the top of said walls adapted to communicate with a water supply and downwardly inclined spaced ports in each of said walls opening at one end into said passage and at the other end at the inner faces of said walls.

3. A bathtub including an open top integral body formed of a bottom, front, rear and side

walls, said front wall being of angle-shape contour and having an intermediate part thereof directed inwardly to provide a seat within said body extending from one side wall to the other, elevated above and over a portion of said bottom 5 and spaced from said rear wall, said walls provided with means at their upper ends for directing a water shower therefrom in a direction towards the back, sides and front of occupant of the tub, said means consisting of a hollow bead 10 directed outwardly from the upper end of the front wall and a hollow bead directed inwardly from the top of each side wall and said rear wall, the said several hollow beads communicating to provide an endless water passage having one portion thereof disposed outwardly with respect to the inner face of the front wall and the remaining portion thereof disposed inwardly with respect to the inner faces of the side and rear walls, said means further including ports in the front wall 20 extending inwardly from said chamber and ports in the beads on the side and rear walls extending inwardly from said chamber, and the said portion of said bottom constituting an extension free of said walls and opposing in spaced relation the 25 said inwardly extending part.

4. A bathtub including an open top integral body formed of a bottom, front, rear and side walls, said front wall being of angle-shape contour and having an intermediate part thereof 30 directed inwardly to provide a seat within said body extending from one side wall to the other, elevated above said bottom and spaced from said rear walls, said walls provided with means throughout their upper ends for directing a water 35 shower therefrom in a direction towards the back, sides and front of occupant of the tub, said means providing an endless water passage adapted to communicate with a water supply and downwardly inclined ports opening at one end into said 40 passage and at the other end into the tub, and said bottom being formed with a portion free of said walls and opposing in spaced relation the said inwardly extending part.

5. A bathtub comprising an open top integral 45 hollow body providing a vertical chamber having its upper portion of greater dimensions than its lower portion, said body having means arranged therein and above the bottom of said chamber to provide a seat for the user of the tub, said body 50 in proximity to its upper end provided with means extending inwardly from the side and rear walls and outwardly from the front wall for directing water, in a shower-like form, in a direction towards the back, sides and front of the user, and 55 the said water directing means providing an endless water conducting passage throughout the upper end of the tub adapted to communicate with a water supply and spaced downwardly inclined ports extending from said passage and 60 opening into said chamber.

6. A bathtub comprising an open top one-piece hollow body formed with a pair of sides and a rear and a front wall, said front wall being of angle-shape contour in vertical section and formed of 65 an upper vertical portion, an inwardly extending intermediate portion and a lower vertical portion, said intermediate portion merging into the lower end of the upper portion and into the upper end of said lower portion, the said upper portion being formed at its upper end with an outwardly directed hollow bead, said lower portion merging into said bottom adjacent the front and rear thereof, said side walls being substantially of inverted L-shape contour and each provided at its 70

- upper end with an inwardly directed hollow bead, said rear wall being straight and provided at its upper end with an inwardly directed hollow bead, said inwardly extending portion of said front wall 5 constituting a seat and opposing in spaced relation a portion of said bottom, said hollow beads merging into each other to provide an endless water chamber throughout the top of said body adapted to communicate with a water supply, the upper portion of said front wall being formed 10 with downwardly inclined ports leading from said chamber to the interior of said body, and the beadings on the side and rear walls being formed with downwardly inclined ports leading from said 15 chamber to the interior of said body.
7. In a bathtub, an open top one-piece hollow body formed of a bottom and front, side and rear walls, said front wall being formed with means to constitute a seat for the occupant of the tub, said front wall having its upper end formed with an outwardly directed hollow bead, said side and rear walls being formed at their upper ends with inwardly extending hollow beads, the said several beads merging into each other to provide an endless water chamber throughout the top of said body adapted to communicate with a water supply, said front wall having its upper portion 10 formed with downwardly inclined ports leading from said chamber to the interior of said body, and the beads on the said side and rear walls being formed with downwardly inclined ports leading from said chamber into the interior of 15 said body.
